UNITED STATES PATENT OFFICE

LEE H. MAHON, OF NORPHLET, ARKANSAS

CASING SUSPENSION HEAD

Application filed January 19, 1927. Serial No. 162,164.

This invention aims to provide a novel casing head whereby a pipe, generally known as the oil string, may be suspended from the upper end of the surface casing of an oil well.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that changes in 15 the precise embodiment of the invention herein disclosed, may be made within the scope of what is claimed, without departing from the spirit of the invention.

In the drawings:—

20 Figure 1 shows in elevation, a device constructed in accordance with the invention;

Figure 2 is a longitudinal section wherein parts appear in elevation;

25 Figure 3 is a cross section on the line 3—3 of Figure 1.

The device forming the subject matter of this application includes a tubular body 1, provided at its upper end with an outstanding flange 2. In the lower end of the tubular body 1 there is a cylindrical bore 3. The body 1 has a conical bore 4 located above the cylindrical bore 3. At the place where the bores 3 and 4 join, there is an internal shoulder 5 in the body 1. The lower end of the body 1 is externally threaded, as shown at 30 6, so that it may be mounted in the upper end of a surface casing 25. The body 1 has any desired number of transverse openings 7, these openings 7, preferably, being located 35 between the upper end of the threading shown at 6 and the shoulder 5.

The pipe or oil string that is to be connected with the upper end of the surface casing 25 is marked by the numeral 8. The pipe 8 extends 40 downwardly through the bore 3 of the body 1. A plurality of yieldable packing members 9, such as rings, are superposed on each other, and are disposed about the pipe 8, the lowermost of the packing members 9 resting on the shoulder 5. The uppermost pack-

ing member 9 is engaged by a foot piece 10, preferably a metal ring. The foot piece 10 is engaged by a plurality of pressure members 11, disposed about the pipe 8 and curved to conform to the pipe. The outer surfaces 55 of the pressure members 11 are smooth and these surfaces cooperate with the conical bore 4 of the body 1, the pressure members 11 being wedge-shaped in longitudinal section. The pressure members 11 are supplied at 60 their inner edges with transverse teeth 12 adapted to engage the pipe 8. At their upper ends, the pressure members 11 have outstanding arms 14, overhanging the flange 2 of the body 1. Fastening devices are supplied, 65 the fastening devices preferably being in the form of screws 15 mounted to rotate in the arms 14 of the pressure members, the screws 15 being threaded into the flange 2 of the body 1, and the heads of the screws engaging 70 the arms 14 of the pressure members.

By threading down the screws 15, the pressure members 11 will be moved downwardly, the lower ends of the pressure members bearing 75 on the foot piece 10, and the foot piece 10 compacting the packings 9 about the pipe 8 to secure a fluid-tight joint between the oil string 8 and the member 1, the gas and water pressure being relieved through the openings 7 instead of passing upwardly about the 80 pipe 8. The pipe 8 often is of great length, and by suspending the pipe 8 as shown, the slack is taken out of it. The teeth 12 on the pressure members 11, cooperating with the pipe 8, tend to hold the pressure members 85 in the position to which they may have been advanced.

What is claimed is:—

A device of the class described, characterized by the provision of individually adjustable and individually removable pressure members, said device comprising a body having an internal shoulder, a packing means in the body and engaging the shoulder, the aforesaid pressure members being wedge-shaped, each pressure member operating independently of the other pressure members, the pressure members engaging the packing means and being movable longitudinally within the body, the pressure members hav- 90 95 100

ing separate outstanding arms overhanging the outer surface of one end of the body, whereby all of the pressure members may be removed, leaving the body in place, and an individually operable fastening device passing through and engaging each of the outstanding arms of the pressure members, the fastening devices being mounted adjustably at their inner ends in said end of the body, whereby each pressure member may be removed independently of the others while pressure is upon said other pressure members.

10 In testimony that I claim the foregoing as my own, I have hereto affixed my signature.

LEE H. MAHON.
